DESIGN FOR A POLO SHIRT OR SIMILAR ARTICLE

Edward Guttman, New York, N. Y.

Application November 5, 1946, Serial No. 134,517

Term of patent 3½ years

(Cl. D3—25)

To all whom it may concern:

Be it known that I, Edward Guttman, a citizen of the United States of America, residing in New York city, county of New York, and State of New York, have invented a new, original, and ornamental Design for a Polo Shirt or Similar Article, of which the following is a specification, reference being had to the accompanying drawing, forming part thereof, wherein, the figure is a front elevational view of a polo shirt showing my new design.

The rear of the polo shirt is substantially plain in appearance.

I claim:

The ornamental design for a polo shirt or similar article, substantially as shown and described.

EDWARD GUTTMAN.
